UNITED STATES PATENT OFFICE.

LILLIAN A. BARTHOLOMEW, OF NEW YORK, N. Y.

DESIGN FOR A PEDESTAL-PINCUSHION.

SPECIFICATION forming part of Design No. 35,981, dated July 22, 1902.

Application filed March 18, 1902. Serial No. 98,844. Term of patent 3½ years.

To all whom it may concern:

Be it known that I, LILLIAN A. BARTHOLOMEW, a citizen of the United States, residing at 381 Sixth avenue, in the city and county of New York and State of New York, have invented and produced a new and ornamental Design for Pedestal-Pincushions, of which the following is a specification, reference being had to the accompanying drawings, forming part thereof.

Figure 1 is a side view. Fig. 2 is a top view.

As shown in the drawings, the leading or material feature of my design consists of a curved oblong ornamental pincushion B, supported in the middle of its concave under surface by a standard C and having its top convex surface for the reception of pins and having its two sides ornamented with ruffles. Or-

namental tasselings D and fringe E are ornamenteally arranged pendent from the center of the cushion B at the top of the standard C. Another bunch of fringe E ornaments the base of the standard C where it joins the base-piece F.

Having described my invention, what I claim as new, and desire to secure by Letters Patent, is—

The ornamental design for a pedestal-pincushion, as herein shown and described.

In testimony whereof I have signed my name to this specification in the presence of two subscribing witnesses.

LILLIAN A. BARTHOLOMEW.
